QUICK-OPENING TANK TRUCK PLUG

George H. Clay, Kansas City, Mo.

Application April 21, 1934, Serial No. 721,752

3 Claims. (Cl. 220—32)

This invention relates to quick-opening tank truck plugs or covers, and has for one of its objects to produce a closure member for tanks, but which is particularly adapted for the filling openings in truck tanks or the like used for the storage or transportation of volatile liquids.

Another object of the invention is to produce a closure of the type mentioned which is adapted to be unseated to relieve pressure within the tank if pressure should be developed therein sufficient to overcome the yielding pressure with which the closure is seated.

A further object of the invention is to produce a closure of the character set forth in which the closure and clamping members have limited movement independently of each other so that the former can always seat squarely to seal the filling opening, regardless of irregularities in the seat or in the direction of the clamping force with regard to the plane of the valve seat.

A still further object of the invention is to produce a strong, durable, efficient and inexpensive mechanism of the character set forth; and in order that it may be fully understood, reference is to be had to the accompanying drawing, in which:—

Figure 1 is a perspective view of a portion of a tank, provided with an expansion chamber, dome or filling neck equipped with a quick-opening plug or cover embodying the invention.

Figure 2 is a view similar to Figure 1, with the closure thrown to open position.

Figure 3 is an enlarged central vertical section through the parts as they will appear during a pressure relieving operation.

Figure 4 is a fragmental section through the parts to more clearly illustrate one method of securing a clamping pin forming a part of the present embodiment of the invention.

In the said drawing, where like reference characters identify corresponding parts in all of the figures, 1 is a tank, 2 is a filling neck or dome, which is preferably provided with a raised bead 3 to form a valve seat 4 surrounding the filling opening. The filling opening may be provided, as shown, with a down-turned flange 5.

Adapted to fit within the flange 5 is a clamping member 6, provided with a series of cam grooves 7 to receive locking pins 8 inwardly projecting from the face of the flange 5. The pins 8 may be secured in position by welding them as at 9 (Figure 4) to the inner face of the dome. The clamping member 6 is of such diameter as to fit loosely within the neck 5 so that it does not

interfere with the escape of gas as shown by the arrows in Figure 3.

Adapted for sealing engagement with the valve seat 4 is a cover or plug member 10, having external operating handles 11. The cover preferably carries a sealing gasket 12 for contact with the valve seat 4, and said cover has a depending flange 13 slidably telescoping over the upper end of the clamping member 6. The cover and the clamping member are held yieldingly together as regards telescoping movement, as will hereinafter appear, but are held against independent rotation by means of three bolts 14 depending from the inner face of the cover 10 and extending through openings in horizontal flange 15 formed on the clamping member 6, the lower ends of said bolts being headed and expansion springs 16 being interposed between said heads and the under side of the flange 15. It is also to be noted that the telescoping of the two parts 10 and 6 is very loose so that if the clamping member 6 should apply strain at other than right angles to the plane of the valve seat 4, one or more of the springs 16 will yield to permit the cover 10 to properly seal the tank against leakage.

With the construction as described, it will be apparent that rotation imparted through the handles 11 will lock or unlock the cooperating cam clamping mechanism 7 and 8, rotation of the cap 10 being imparted to the clamping member 6 through the three bolts 14. It will also be evident that the cap 10 will fit on the valve seat 4 under the pressure of the springs 16, and that if sufficient internal pressure is built up within the tank, the closure will open as shown in Figure 3 to relieve such pressure, and will then reseat under the force of said expansion springs 16.

As a vacuous condition sometimes is created within tanks of volatile liquids, the cap 10 is provided with a tapped opening 17 receiving a threaded stem 18 of a vacuum release mechanism 19. This mechanism is not detailed or otherwise referred to as it forms no part of the present invention and may be of any desired or approved character.

In tank trucks and the like in particular, means must be provided for locking the filling plug against unauthorized opening and to prevent mislaying or loss of the filling plug as a whole. To accomplish this object, an arm 20 is pivoted on an ear 21 carried by the filling neck or tank, and the end of said arm has an opening receiving the threaded stem 18 of the valve structure 19. The arm 20 is not tightly clamped between the face of the closure and the valve mech-

45

55

anism 19 as such an arrangement might interfere with the proper clamping of the cover on its seat. However, to hold the parts against rattling, a spring 22 is inserted between the upper face 5 of the arm and the vacuum relief valve 19. With this construction it is apparent that the plug bears a swivelled relation to the tank and may be readily rotated so that it can be unlocked and then swung to open position for filling or inspection. To lock the plug against unauthorized opening, its upper face is provided with an 10 standing ear 23 which comes into abutting relation with a companion ear 24 on the arm 20, when the parts are in closed position, and said ears 15 are formed with registering openings 25 for receiving a padlock or the like.

From the above description it will be apparent that I have produced a construction embodying all of the features of advantage set forth as desirable, and while I have described the preferred embodiment, it is to be understood that I reserve the right to make all changes within the spirit of the invention and without the ambit of the prior art.

25. I claim:—

1. In a tank closure, a tank having a filling opening, a depending neck and an upwardly-facing bearing around said opening and three equi-distant pins projecting from the neck into 30 said opening, a dome-shaped cover having a central threaded opening, a peripheral bearing for facing downwardly over the first-named bearing, a circular flange for depending into the filling opening, and three equi-spaced pins for depending 35 from the cover into the filling opening, a circular clamp-member fitting into the cover for telescopic movement relative thereto and for fitting loosely and rotatably within the filling opening and also fitting telescopically upon said depending pins, springs upon said depending pins and exerting force upon the said pins and the clamp member for resisting separating telescopic movement of the cover and clamp-member, 40 operating means on the tank and clamp-member for drawing or repressing the latter and the cover, toward or from the tank respectively when the cover is rotated in one direction or the other, the connection between the cover and clamp-member and the tank permitting of slight tilting movement of the cover relative to the clamp-member,

a gasket between the said bearing faces, a valve having a stem threaded in the opening of the cover, an arm hinged to the tank and fitting between the cover and valve and loosely around the valve stem, and a spring for exerting yielding force in opposite directions on the valve and arm and tending to hold the cover and adjacent end of said arm in contact and in parallelism. 5

2. In a tank closure, a tank having a filling opening, a depending neck and an upwardly-facing bearing around said opening and three equi-distant pins projecting from the neck into 10 said opening, a dome-shaped cover having a central threaded opening, a peripheral bearing for facing downwardly over the first-named bearing, a circular flange for depending into the filling opening, and three equi-spaced pins for depending 15 from the cover into the filling opening, a circular clamp-member fitting into the cover for telescopic movement relative thereto and for fitting loosely and rotatably within the filling opening and also fitting telescopically upon said depending pins, springs upon said depending pins and exerting force upon the said pins and clamp-member for resisting separating telescopic movement 20 of the cover and clamp-member, coacting cam connections between the wall of the filling opening and the clamp-member responsive to rotation of the latter in one direction or the other to respectively draw it and the cover toward or 25 repress them from the tank, a gasket between the said bearing faces, a valve having a stem threaded in the opening of the cover, an arm hinged to the tank and fitting between the cover and valve and loosely around the valve stem, and a spring for exerting yielding force in opposite 30 directions on the valve and arm and tending to hold the cover and adjacent end of said arm in contact and in parallelism. 35

3. In a tank closure, a tank having a filling 40 opening, a cover for such opening, a valve having a threaded stem secured to the top of the cover, an arm hinged to the tank and fitting loosely around said stem between the valve and cover, and means around the stem and exerting 45 yielding force in opposite directions on the arm and valve and tending to hold the contacting surfaces of the former and cover in parallelism.
